[57] CLAIM

The ornamental design for a hairbrush for attachment to a mousse dispensing container or the like, as shown and described.

DESCRIPTION

FIG. 1 is a front elevational view of a hairbrush for attachment to a mousse dispensing container or the like showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of a dispensing container is for illustrative purposes only and forms no part of the claimed design.

The inside of the holder portion of the hair brush is smooth and unornamented.
